139,371

DESIGN FOR A COMBINED HANDBAG AND HAT

Daniel Rubin, New York, N. Y.

Application July 13, 1944, Serial No. 114,384

Term of patent 3½ years

(Cl. D87—3)

To all whom it may concern:

Be it known that I, Daniel Rubin, a citizen of the United States of America, residing in New York city, county of New York, and State of New York, have invented a new, original, and ornamental Design for a Combined Handbag and Hat, of which the following is a specification, reference being had to the accompanying drawing, forming part thereof, wherein,

Figure 1 is a front elevational view of a combined handbag and hat showing my new design.

Figure 2 is a side elevational view.

Figure 3 is a view similar to Figure 1, the hat member being lifted in order to illustrate the handbag.

Figure 4 is a rear elevational view of Figure 1, and

Figure 5 is a bottom plan view, drawn on a smaller scale.

I claim:

The ornamental design for a combined handbag and hat, substantially as shown.

DANIEL RUBIN.
